US00D782985S

(12) **United States Design Patent** (10) **Patent No.:** **US D782,985 S**
(45) **Date of Patent:** **** Apr. 4, 2017**

(54) **HEAT PAD CONTROLLER**

(71) Applicant: **E. Mishan & Sons, Inc.**, New York, NY (US)

(72) Inventor: **Steven Mishan**, New York, NY (US)

(73) Assignee: **E. Mishan & Sons, Inc.**, New York, NY (US)

(**) Term: **15 Years**

(21) Appl. No.: **29/562,344**

(22) Filed: **Apr. 25, 2016**

(57) **CLAIM**

The ornamental design for a heat pad controller, as shown and described.

DESCRIPTION

FIG. 1 is a front, top right perspective view of a heat pad controller showing my new design therefor;

FIG. 2 is a bottom, rear left perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines show portions of the heat pad controller that form no part of the claimed design.

1 Claim, 5 Drawing Sheets
